TRAILER ELECTRICAL CONNECTOR TESTER OR SIMILAR ARTICLE

Gilbert G. Lemmenes, South Gate, Calif.

Application July 17, 1958, Serial No. 51,820

Term of patent 14 years

(Cl. D26—1)

FIG. 1

FIG. 2

Fig. 1 is a perspective view of a trailer electrical connector tester or similar article showing my new design; and

Fig. 2 is a side elevational view thereof. The back, not shown, is conventional.

I claim:

The ornamental design for a trailer electrical connector tester or similar article, as shown and described.
